No. 854,602.

PATENTED MAY 21, 1907.

G. W. PETERSON.

TRUNK.

APPLICATION FILED MAY 16, 1906.

UNITED STATES PATENT OFFICE.

GEORGE WILLIAM PETERSON, OF LEONARDVILLE, KANSAS.

TRUNK.

No. 854,602.

Specification of Letters Patent.

Patented May 21, 1907.

Application filed May 18, 1906. Serial No. 317,124.

To all whom it may concern:

Be it known that I, GEORGE WILLIAM PETERSON, a citizen of the United States, residing at Leonardville, in the county of Riley and State of Kansas, have invented a new and useful Trunk, of which the following is a specification.

The invention relates to improvements in trunks.

10 The object of the present invention is to provide a simple, inexpensive and efficient attachment for trunks, adapted to be readily operated for causing a pair of wheels to project from the bottom of a trunk at one end 15 thereof, for enabling the same to be quickly and easily wheeled from one point to another.

A further object of the invention is to provide a device of this character, which, when not in use, will be housed within the trunk, 20 and which will not permit dust or other substances to enter the same.

With these and other objects in view, the invention consists in the construction and novel combination of parts hereinafter fully 25 described, illustrated in the accompanying drawings, and pointed out in the claims hereto appended; it being understood that various changes in the form, proportion, size and minor details of construction, within the 30 scope of the claims, may be resorted to without departing from the spirit or sacrificing any of the advantages of the invention.

In the drawing:—Figure 1 is a vertical longitudinal sectional view of a trunk provided with an attachment constructed in accordance with this invention. Fig. 2 is a horizontal sectional view of the same. Fig. 3 is an enlarged detail sectional view illustrating the arrangement of the parts when 40 the caster wheel is projected. Fig. 4 is a detail perspective view of the vertical movable member, which carries the caster wheel. Fig. 5 is an enlarged detail sectional view on the line 5—5 of Fig. 3. Fig. 6 is a similar 45 view on the line 6—6 of Fig. 3.

Like numerals of reference designate corresponding parts in all the figures of the drawing.

1 designates a trunk, which is provided at 50 each side with a longitudinal casing 2, arranged horizontally and located at the lower portion of the trunk and having a depending arm or portion 3, which extends downward from the horizontal body portion of the casing 55 to an opening 4 in the bottom of the trunk. The casing, which is preferably con-

structed of sheet metal, is provided at its sides with projecting attachment flanges 5 and 6, which are perforated for the reception of rivets, or other suitable fastening devices, 60 for securing the casing to the trunk. The casing is slightly enlarged adjacent to the depending arm or portion 3 to receive a vertically movable member 7, consisting of a vertical body portion, which is slidable in a vertical guide 8. The vertically movable member 7 is provided at its lower portion with a projecting caster wheel 9, which is mounted on a transverse spindle 10, and the latter is supported at one end by the vertically movable 65 member and at the other end by a bracket 11, but the caster wheel may be mounted on the vertically movable member in any other desired manner, as will be readily understood.

75 The guide 8, which is secured to the trunk by rivets, or other suitable fastening devices, is provided at opposite sides with guide flanges 12, which are substantially L-shaped in horizontal section to embrace the side 80 edges of the vertically movable member. The guide is secured to the trunk by means of rivets 13, or other suitable fastening devices, which pass through suitable ears of the guide. The vertically movable member is 85 provided at its upper end with an arm 14, arranged substantially at right angles to the body portion of the vertically movable member, and provided at its outer end with a headed stud 15, which is arranged in an inclined guide 16 of a horizontally movable member 17. The horizontally movable member 17, which is slidable in a horizontal guide 18, is provided with an inclined slot to form the guide 16. The inclined slot provides inclined upper and lower edges, which are adapted to engage the headed stud 15 to force the vertically movable member either upwardly or downwardly. This will enable the caster wheel to be either projected 95 from the bottom of the trunk, or withdrawn into the same. The headed stud may be provided with an anti-friction sleeve and the horizontal guide 18, which is riveted or otherwise secured to the trunk, is provided with 100 upper and lower horizontal guide flanges which are L-shaped in cross section to embrace the horizontally movable member 17.

105 The horizontally movable member is operated by a bar or rod 19, which extends along the casing 2 to the farther end of the trunk, and the latter is provided with a corner open-

ing 20, communicating with the casing and adapted to receive a head 21 of the operating rod or bar 20. The head of the operating bar lies within the opening 20, and is flush with the adjacent faces of the trunk, when the caster wheel is at the limit of its upward movement. The operating rod is adapted to be readily drawn outward, to the position illustrated in dotted lines in Figs. 1 and 2 of the drawing, to project the caster wheel below the bottom of the trunk, as illustrated in full lines in Fig. 3 of the drawing.

Although the attachment is shown applied to a trunk, yet it will be readily apparent that it is applicable to various kinds of receptacles, and other articles, as it will permit such receptacles, or articles to be converted into a wheeled piece for conveniently moving the same.

Having thus fully described my invention, what I claim as new and desire to secure by Letters Patent, is:—

1. In a device of the class described, the combination of a vertical guide, a horizontal guide, a slideable member movable in the vertical guide and provided with a caster wheel, an operating member slideable in the horizontal guide, and means carried by the operating member for raising and lowering the said slideable member.

2. In a device of the class described, the combination with a receptacle provided at the bottom with an opening, a vertical guide extending upwardly from the opening, a horizontal guide, a slideable member mounted in the vertical guide and movable through the opening of the said receptacle and provided with a caster wheel, an operating member slideable in the horizontal guide and having an inclined slot, and means mounted on the first mentioned member and operating in the slot for raising and lowering the caster wheel when the operating member is actuated.

3. In a device of the class described, the combination with a receptacle provided with a bottom opening, a vertically slideable member mounted on the receptacle and movable through the said opening, a horizontally slideable member guided on the receptacle and provided with an inclined slot, a projection carried by the vertically movable member and operating in the slot of the horizontally movable member, and means for operating the latter.

4. In a device of the class described, the combination with a receptacle provided at the bottom with an opening and having an end opening, a member slideable through the bottom opening and carrying a caster wheel, an operating bar mounted within the receptacle and extending through the end opening of the same, and means carried by the operating bar for actuating the said member to raise and lower the caster wheel.

5. The combination with a receptacle provided at the bottom with an opening located near one end of the receptacle, said receptacle being provided at the opposite end with an opening, a vertically movable member carrying a roller and operating through the bottom opening, a horizontally movable member having inclined edges for actuating the vertically movable member, an operating bar connected with the horizontally movable member and extending through the end opening, and a casing mounted on the receptacle and receiving the said members and the operating bar.

In testimony, that I claim the foregoing as my own, I have hereto affixed my signature in the presence of two witnesses.

GEORGE WILLIAM PETERSON.
